UNITED STATES PATENT OFFICE.

CYRIL FREDERICK JOHNSTON AND HARRY NORMAN WALFORD, OF CROYDON AND LEWISHAM, LONDON, ENGLAND.

STRIKING AND CHIMING CLOCK.

Application filed July 2, 1921. Serial No. 482,021.

To all whom it may concern:

Be it known that we, CYRIL FREDERICK JOHNSTON and HARRY NORMAN WALFORD, subjects of the King of Great Britain, and 5 residents of Croydon, in the county of Surrey, and Lewisham, London, England, respectively, have invented certain new and useful Improvements in Striking and Chiming Clocks, of which the following is a 10 specification.

This invention relates to striking and chiming and like clocks and it has for its object to simplify the construction of such 15 clocks by dispensing with one of the usual sets of train gear.

In clocks as now constructed separate 20 train gears are provided to perform separate functions for example in clocks which are adapted to strike both the hours and the quarters there are provided three sets of 25 train gear, one being for the time another for the hour striking and the third for the quarter chiming.

By means of this invention one of these 30 sets of train gear is dispensed with by adapting one of the remaining two sets to periodically perform the functions of the third.

The invention therefore consists broadly 35 of a striking and the like clock wherein a driven train of wheels having one primary function is adapted to be connected and disconnected periodically to perform another or other secondary functions.

According to one embodiment of the invention 40 the ordinary hour striking train is used to operate the quarter chiming mechanism by means of a differential gear the two contrate gear wheels of which are connected to the chiming and striking gear respectively and are adapted to be alternatively locked 45 against movement whereby the one set of train gear effects the operation of both the chiming and hour striking mechanisms.

In order that the invention may be clearly 50 understood an embodiment of the same will now be described by the aid of the accompanying drawings in which:

Fig. 1 is a perspective view looking 55 towards the front of the mechanism, parts not material to the proper understanding of the invention being omitted.

Fig. 2 is a similar view looking towards 60 the rear of the mechanism.

vation of a modification hereafter to be described, and

Fig. 3 is a longitudinal part sectional ele- Fig. 4 is a side elevation of a modification.

The embodiment of the invention illus- 60 trated in the drawings comprises a pair of contrate spur wheels 1 and 2 loosely mounted upon an arbor or spindle 3 and opera- tively connected by means of one or more interposed pinions 4. These pinions are car- 65 ried by a spider 5 which is fixedly secured to the arbor or spindle 3 so as to rotate therewith.

The contrate wheel 1 is adapted to operate 70 the hour striking hammer 6 for which purpose the same is provided on its outside face with a plurality of spaced pins 7 which successively contact with a trip lever 8 which effects the striking movement of the hammer 6 in a well known manner.

These pins 7 also serve another purpose as 75 will hereafter appear.

The other contrate wheel 2 is connected 80 to a drum 9 the periphery of which is provided with a plurality of predeterminedly spaced pins 10 which effect the tripping of the chiming hammers 11 in their proper order according to the arrangement of the notes as exemplified by the sound producing devices not shown.

The arbor or spindle 3 carries at one end 85 a half wheel 12 which is driven by the hour striking train of wheels referred to generally by the reference numeral 13 and thereby imparts the necessary rotational move- 90 ment of the said arbor or spindle.

To effect alternate operation of the hour 95 and quarter striking hammers it is necessary to lock one or other of the contrate wheels 1 or 2 against movement. For this purpose we provide what may be conveniently termed a bell crank lever comprising the two arms 14 and 15 projecting from a common boss 16 which in turn is fixedly mounted upon an oscillatable spindle 17. The arm 14 is forked at its outer or free end by the for- 100 mation therein of a slot 18 which is adapted to periodically engage one of the pins 7 so as to effect the desired locking of the contrate wheel 1. The outer end of the other arm 15 is provided with a projecting pin 19 which periodically engages in a slot 20 cut in the periphery of a flange 21 of the contrate

wheel 2 so as to similarly effect the locking of said contrate wheel 2 when the other contrate wheel 1 is free and vice-versa.

The rocking shaft 17 is operated by means of pins 22 carried at diametrically opposite points by a tooth wheel 23 the arbor 24 of which carries the usual quarter chime controlling snail 25, through the medium of a pump lever 26 which is rigidly mounted upon the front end of said rocking shaft. In operation the rotation of the toothed wheel 23 causes the pin 22 to periodically engage the free end of the pump lever 26 thereby displacing said lever in one direction so as to move the rocking shaft 17 and bring the slot 18 in the end of the arm 14 into engagement with one of the pins 7 for the purpose above mentioned. The continued movement of the pin 22 allows the pump lever 26 to move inwards towards the arbor 24 by gravity thereby moving the pin 19, carried by the other arm 15 into engagement with the slot 20, the slotted arm 14 simultaneously moving out of engagement with the positioned pin 7.

In the modification illustrated in Fig. 3 the pinion or pinions of the differential are rigidly mounted upon radial spindles 27 which in turn are revolubly mounted within bearings in a ring frame 28 which is secured upon the arbor or spindle 3.

From the foregoing description it will be understood that when the contrate wheel 1 is locked against movement the rotation of the arbor or spindle 3 is imparted only to the drum 9 which as a consequence operates the chiming hammers 11. Conversely when the contrate wheel 2 is locked against movement the rotation of the arbor or spindle 3 imparts motion to the contrate wheel 1 which as a consequence operates the hour striking hammers 6. It will also be understood that the order of these operations is controlled by the position of the pins 22 which in turn are in predetermined relationship to the position of the usual hour and chime striking snails.

In the modification illustrated in Fig. 4 the spring drum 29 and fuses 30 are utilized

to operate both the time and the hour chiming gears for which purpose a differential gear is mounted upon the fusee arbor or spindle 31. The contrate wheel 32 of the differential is provided with a spur wheel 33 which drives a pinion 34 on the time spindle 35. The other contrate wheel 36 is also provided with a spur wheel 37 which drives a pinion 38 mounted upon an arbor or spindle 39 which carries a disc 40 having a plurality of projecting pins 41 corresponding to the pins 7 in the other previously described examples and serving to operate the hour striking hammer in a similar manner. The differential pinion which meshes with the contrate wheels 32 and 36 is indicated at 42.

In this modification the time or hour striking mechanism may be connected for operation by engagement with pins 41 of a lock lever as 14 in Figure 1, and the chime mechanism may be locked by a lock device similar to arm 15.

What we claim and desire to secure by Letters-Patent is:—

1. The combination in a clock striking mechanism with a pair of trains each including a driven gear, of a differential pinion and its driving spindle for operating said trains, a periodically movable rock shaft and lock arms thereon for selectively engaging said trains whereby one train is held while the other train is actuated.
2. The combination in a clock striking mechanism with a driving spindle and differential pinion thereon, of a chime actuating drum loose on the spindle and provided with a gear, a striking trip wheel loose on the spindle and provided with a gear at the opposite side of the differential pinion, a periodically movable rock shaft, and lock arms on said shaft for selectively engaging said drum and trip wheel whereby one is held while the other is actuated.

In witness whereof we affix our signatures.

CYRIL FREDERICK JOHNSTON.
HARRY NORMAN WALFORD.
